UNITED STATES PATENT OFFICE.

FRANCIS T. SMYTHE, OF ST. LOUIS, MISSOURI.

FLOATING WATER-ELEVATOR.

SPECIFICATION forming part of Letters Patent No. 320,184, dated June 16, 1885.

Application filed March 9, 1885. (No model.)

To all whom it may concern:

Be it known that I, FRANCIS T. SMYTHE, a citizen of the United States, residing at St. Louis, in the county of St. Louis and State of Missouri, have invented a new and useful Improvement in Floating Water-Elevators, of which the following is a specification, reference being had to the accompanying drawings.

10 My invention relates to an improvement in floating water-elevators; and it consists in the peculiar construction and combination of devices, that will be more fully set forth hereinafter, and particularly pointed out in the 15 claims.

15 In the accompanying drawings, Figure 1 is a side elevation of a machine embodying my invention. Fig. 2 is a top plan view of the same.

20 My invention is particularly designed to irrigate lands adjacent to water-courses.

25 *a* represents a pair of twin floats, which are arranged parallel to each other, and secured at a suitable distance apart by the beams *b c*. The inner side of the front end of each of the floats is made angular, as at *d*, so as to direct the current of the stream in which the floats are moored between said floats, and thereby secure increased strength of the current at this point.

30 *d'* represents a shaft that is journaled in bearings *e*, and extends from one float to the other at a suitable distance above the floats, as shown. An undershot water-wheel, *f*, is fixed to the shaft *d'*, and is rotated by the current of the stream.

35 To the ends of the shaft *d* are fixed large spur-wheels *g*, that mesh with pinions *h*, which are fixed to the shafts *i*. The shafts *i* are 40 journaled in movable blocks *k*, that allow a slight play of the inner ends of the shafts *i*, and levers *l* are pivoted to the floats and connected to the shafts. By moving the levers back or forth the shafts can be moved so as

45 to cause the pinions *h* to mesh with the gear-wheel *g* or to be disengaged therefrom.

To the outer ends of the shafts *i* are secured crank-wheels *m*.

50 Pumps *n* are secured to the outer sides of the floats, and the plunger-rods of these pumps are connected to the crank-wheels by con-

necting rods *o*. As the paddle-wheel is revolved by the action of the current, the pumps are worked thereby, and the water raised from the stream by the pumps can be conveyed by 55 suitable pipes to any desired point. The pumps *n* are ordinary force or lift pumps.

At *p*, I show a chain-pump, which may be employed, if preferred. In this instance a chain-wheel, *m'*, is substituted for one of the 60 crank-wheels *m*, and the endless chain of the pump is moved by the wheel *m'*, as shown.

A floating water-elevator thus constructed is adapted to be operated by the current of a stream, and will be found very valuable for 55 irrigating purposes.

Having thus described my invention, I claim—

1. The twin floats *a*, arranged parallel to each other and secured together, in combination with the water-wheel journaled between the floats, the gear-wheel *g*, fixed to the shaft of the water-wheel, the shafts *i*, swiveled loosely at one end in blocks attached to the floats, the movable blocks *k* on the other ends of the 70 shafts, pinions *h* on the latter meshing with the gear *g*, levers *l*, pivoted to the floats and connected to the shafts *i*, and the pumps connected to the latter, as set forth.

2. The floats *a*, arranged parallel to each other, and secured at a suitable distance apart by the beams *b c*, the inner side of the front end of each float being set at an angle, *d*, to the outer side, in combination with the shaft *d'*, journaled in bearings of the floats, a water-wheel mounted on the shaft, gear-wheels *g*, fixed on the ends of the shaft *d'*, the shafts *i*, swiveled loosely at one end in blocks attached to the floats, the movable blocks *k* on the other ends of the shafts, guides for said blocks to 85 move in, pinions *h*, mounted on the shafts and adapted to mesh with the gear *g*, levers *l*, pivoted to the floats and connected to the shafts *i*, and the pumps connected to the latter, for the purpose set forth.

In testimony that I claim the foregoing as my own I have hereto affixed my signature in presence of two witnesses.

FRANCIS T. SMYTHE.
